MARKING INSTRUMENT

William Kaufman, Great Neck, N. Y.

Application October 25, 1951, Serial No. 253,144

3 Claims. (Cl. 33—23)

1

My invention relates to a new and improved marking instrument.

Without limitation to any use, the invention is particularly useful in marking one or more scribed garment patterns or other figures from an original garment pattern or other figure. The scribed garment patterns may be larger or smaller than the original pattern or figure.

Devices for this purpose have been described in Anderson U. S. Patent No. 184,493, dated November 21, 1876; Cote U. S. Patent No. 469,775, dated March 1, 1892; Hobson U. S. Patent No. 2,415,283, dated February 4, 1947, and many other patents.

These prior devices have not gone into commercial use, because they did not have sufficient accuracy and simplicity.

According to one embodiment of my invention, I provide an arm which has a straight longitudinal axis, and which is of adjustable length in the direction of said axis. Said arm is associated with a support, which has a planar face and which can support a sheet of paper or other markable material in planar form. A selected guide-point on said axis is guided to move in a selected straight-line guided path relative to said planar supporting face. Said arm overlies said planar supporting face. Said guide-point may be an end-point of said arm, but the invention is not limited to this feature. Said arm is provided with a pivot on said axis, at a pivot-point which is spaced longitudinally from said guide-point. Said pivot-point is spaced longitudinally from the ends of said arm. Means are provided for guiding said pivot-point to move in a pivot-point path which is perpendicular to said first-mentioned guided path.

Said arm is provided with at least one tracer on a selected tracer point of said axis and with at least one scribe on a selected scribe point of said axis. Said arm may be provided with any selected number of such tracers and scribes.

For convenience, the direction of said first-mentioned guided path is designated as the X-axis or X-direction, and every line of the figure to be copied, which is parallel to said first-mentioned guided path, is designated as an X-line or X-direction line. Likewise, the direction of said pivot-point-path is designated as the Y-direction or Y-axis and all lines of said figure which are parallel to said pivot-point-path are designated as Y-lines or Y-direction lines.

For convenience, it is assumed that the arm has one scribe and one tracer, which are spaced longitudinally from each other.

2

The scribe marks a marked figure which corresponds to the original figure over which the tracer is moved.

The marked figure may be smaller or larger than the original figure.

I thus provide a very simple instrument in which the width of the original figure may be reduced or enlarged in greater proportion than the height of the reduced figure.

Thus, if the original figure is a circle, and the scribe is closer to the pivot than the tracer, and the scribe is closer to said guided-point than the tracer, the marked figure will be an ellipse whose major axis is of less length than the diameter of said circle. Said major axis will be in the Y-direction. The minor axis of said ellipse will be in the X-direction. In this example of the invention, the reduction in width is greater than the reduction in length.

An important feature resides in my provision of improved means for guiding the pivot-point in the Y-direction, comprising a front frame connected by a universal joint to the adjustable arm at said pivot-point, and means coupling said front frame to a pedestal located rearwardly of the guide means for moving the pivot point in the X-direction.

Other objects and advantages and features of my invention are disclosed in the annexed description and drawings, which disclose preferred embodiments of the invention.

In the embodiments illustrated herein, the adjustable-length arm is a lazy-tongs arm.

Fig. 1 is a top plan view of one preferred embodiment of the improved instrument, showing the lazy-tongs arm in three different positions;

Fig. 2 is a side view of Fig. 1;

Fig. 3 is a detail perspective view which applies to both embodiments; and

Figs. 4 and 4A are partial top plans of respective modifications.

When the tracer and scribe are fixed to the lazy-tongs arm, and said arm is of any operating length, certain dimensions are identified as follows: 4-26 is the distance along the axis of the lazy tongs between the guide-point and the pivot-point; 4-T is the distance between said guide-point and the point of the tracer along said axis or in a direction parallel to said axis; 4-S is the distance between said guide-point and the point of the scribe along said axis or in a direction parallel to said axis; 26-T is the distance between said pivot-point and the point of said tracer along said axis or in a direction parallel to said axis; 26-S is the distance between said

3

pivot point and the point of said scribe along said axis or in a direction parallel to said axis; and T-S is the distance between the points of said tracer and scribe along said axis or in a direction parallel to said axis.

The ratio

$$\frac{4-S}{4-T}$$

is always constant, irrespective of the length and position of the arm. The ratio

$$\frac{26-S}{26-T}$$

is also always constant, irrespective of the length and position of the arm. The distance 4-T is greater than the distance 4-S, as shown in Fig. 1. If the tracing point and the scribing point are interchanged, then the distance 4-T is less than the distance 4-S. Similarly, the distance 26-T is greater than the distance 26-S, as shown in Fig. 1. If the tracing point and the scribing point are interchanged, then the distance 26-T is less than the distance 26-S.

The ratio between the lengths of corresponding X-lines or X-dimensions of the original and marked figures is the constant ratio

$$\frac{26-S}{26-T}$$

The ratio between the lengths of corresponding Y-lines or Y-dimensions of the original and marked figures is the constant ratio

$$\frac{4-S}{4-T}$$

In order to provide a series of marked garment patterns which correspond to a master pattern, the ratio between the width of each marked pattern and the width of the master pattern, is different from the ratio between the height of each marked pattern and the height of the master pattern. In practice, the instrument is provided with a single tracer and with a series of scribes, so as to provide a plurality of respective distances 4-S and 26-S for each distance 4-T and 26-T, keeping the aforesaid ratios constant while said distances are varied. The aforesaid ratios are selected by suitably dimensioning and proportioning the instrument, so that the scribes mark a selected range of scribed patterns for different selected sizes, corresponding to the size of the master pattern.

A transverse channel guide-rail 2 is fixed to table 1. Roller 3 has an integral vertical pivot stud 4, which fits closely and slidably in the transverse slot in the top wall of rail 2. Roller 3 can freely slide and rotate relative to guide rail 2.

For convenience, the median line of the top slot of guide-rail 2, which intersects the vertical axis of pivot-stud 4, is designated as the X-axis. Hence, lines 35a and 35 are X-lines.

The lines 32, 32a, 36a and 36 are Y-lines.

The rear end of the adjustable arm, whose length can be increased or decreased, is pivotally connected to pivot stud 4, so that said rear end can turn freely around the vertical axis of pivot stud 4. Said rear end can also move along rail 2. This rear end is said selected guide point.

In this illustrative embodiment, said variable-length arm is a lazy-tongs arm and has a plurality of arm-elements, which include the rear arm-element E and the front arm-element Ea.

4

Said variable-length arm may have any desired number of said arm-elements, and said arm-elements may be of any size.

The lazy-tongs arm consists of a number of bars, each of which has one or more bar-sections. All said bar-sections are of the same length. The circles in Fig. 1 indicate pivots which connect the crossing-points of respective bars. Only some of these pivots are indicated by reference numerals. The distance between successive pivot points on a bar is a bar section.

The rear arm-element E consists of bar 5, bar

6, two bar-sections of bar 6a, two bar-sections of bar 5a, two bar-sections of bar 12, and two bar-sections of bar 9. Pivots 7a, 8, 7 and 4 are at the corners or vertices of arm-element E. Pivots 14 and 16 are respectively equi-distant from pivots 7a and 4, 8 and 7.

Pivot 15 is equi-distant from pivots 14 and 16.

Basically, each element is a parallelogram with four sides of identical length.

The end-section of bar 9 is connected by pivot 9a to bar 18, which has four sections. Bar 5a is pivotally connected to one end of bar 17. Bars

17 and 18 are pivotally connected to bars 20 and 19. Bars 17 and 19 are connected by the corner or vertex pivot 8a. Bar 20 is provided with pivots 20a and 20b. Bar 19 is connected to bar 17a, which is connected by corner or vertex pivot 8b to bar 19a.

The front arm-element Ea has an edge-bar which comprises two sections of bar 19a, another edge bar which comprises two sections of bar 17a, a bar 19b, and one of the bars 21.

Fig. 1 is substantially to scale.

As previously noted, the arm-elements may be of any size, so that front arm-element Ea can have any selected number of bars 21. The pivots of these bars 21 are equally spaced. Arms 21 always remain parallel to each other and to bar 17a.

Arms 21 have respective sockets or holders 22. A tracer T is located in one of the holders 22, as in the front socket 22. A scribe S is located in any other socket S. If desired, respective scribes S can be located in all the sockets 22, with the exception of the socket which is occupied by tracer T.

This embodiment shows four arm-elements, which have respective corner or vertex pivots 4, 8, 8a, 8b and the vertex pivot which connects the front end of front bar 21 to bar 19b. The arm has a straight-line axis which overlies and is parallel to the planar and horizontal top of table 1. In this embodiment, said axis is the common diagonal which intersects the vertical axes of corner or vertex pivots 4, 8, 8a, 8b and the vertical axes of tracer T and scribe S.

The ends of bars B are pivoted to selected points of bars 5a and 20, 18 and 6a. A vertical pivot-pin 26 extends through the vertical bore of sleeve 25 and the aligned crossing points of bars B. Said pivot-point is on the vertical axis of pivot-pin 26. Sleeve 25 has bearing sleeves 24a. Shafts 24, which are horizontal and parallel to the X-axis, connect the front bottom end of frame 23 to bearing sleeves 24a. Pivot pins 27, which are horizontal and parallel to the X-axis, turnably connect the rear upper end of frame 23 to the front upper end of rear frame 28. Pedestal 30, which is fixed to table 1, has a bearing 30, in which the horizontal shaft 29 is located. Shaft 29 is parallel to the X-axis and it turnably connects frame 28 to pedestal 30. Frame 28 has

counterweights 31. These frames 23 and 28 con-

stitute the means for guiding and forcing pivot pin 26 to move along a single Y-line, in all positions of the arm.

Pivot 26 may be located at any selected point of said axis or common diagonal line. In this illustrative embodiment, but without limitation thereto, the distance 4-26, on the axis of the arm, between the vertical axes of pivots 4-26, is one-third of the distance 4-T.

A universal joint connection is provided between frame 23 and the arm.

The original or master figure or pattern P is on a master sheet of paper which is fixed to the top of table 1 in any suitable position, such as the position shown in Fig. 1.

Fig. 1 shows that master pattern P has Y-lines 32 and 36, and an X-line 35, which intersects X-line 36.

The scribe S is a stylus in this embodiment. The scribed or marked pattern Pa is marked on a sheet of copy paper which is fixed to the horizontal and planar top of table 1, below the master sheet. A sheet of carbon paper is located between the master sheet and the copy sheet. When tracer T, which is also a stylus, is moved over the outline of pattern P, said scribe S makes a carbon marking of pattern Pa.

Said pattern Pa has scribed Y-lines 32a and 36a which correspond respectively to master Y-lines 32 and 36, and a scribed X-line 35a which is parallel to X-line 35 and hence to the X-axis.

Line 32 has end points 33 and 34. Line 32a has end points 33a and 34a. Line 35a intersects line 36a at point 39.

If line 32a be extended, it intersects line 35 at point 37.

When tracer T is at point 33, scribe S is at point 33a, and roll 3 is in its right position of Fig. 1.

When roll 3 is in its median position of Fig. 1, said common diagonal line or axis of the variable-length arm is a Y-line, tracer T is then on line 35, and scribe S is then on line 35a, as shown in one broken-line position of the arm in Fig. 1.

When tracer T is at the top of master line 36, scribe S is at the top of line 36a, and roll 3 is in its left position of Fig. 1.

The X-lines 35a and 35 are designated as "width" lines.

When tracer T is moved from point 33 along master line 35 to the intersection of lines 35 and 36, scribe S is moved along line 35a from point 33a to point 39.

The ratio of the length of line 35a to line 35 is the ratio of the distance 26-S to the distance 26-T. As previously noted, this ratio remains constant and pivot 26 is always on the same Y-line. If scribes S are provided in all the sockets 22 above the socket 22 which holds tracer T, a series of lines will be marked which correspond to line 35a and which will have different respective lengths.

Primarily, the width ratio between the master pattern and the scribed pattern is selected by adjusting pivot 26 along said common diagonal line or axis of the variable-length arm. A change in the positions of tracer T and scribe S will also affect this ratio.

As previously noted, when tracer S is at point 33a, scribe S is in the rear socket 22.

When tracer T is moved along line 32 from point 33 to point 34, scribe S marks line 32a by moving from point 33a to point 34a.

When tracer T is initially at point 33 and scribe S is initially at point 33a, the X-direc-

tion spacing between tracer T and scribe S is the distance 33-37, and the corresponding Y-direction spacing is the distance 33a-37.

In order to illustrate the operation of the instrument, it is assumed that tracer T is moved along an extension of line 32 to the X-axis. In such case, the scribe S is moved automatically from initial point 33a to the X-axis. The X-direction spacing 33-37 remains constant, and in such case, the Y-direction spacing 33a-37 is finally diminished to zero. Hence the maximum difference of length between the lines 32 and 32a is the Y-direction distance 33a-37.

When tracer T is at point 33, the angle of said common diagonal line with X-line 35 is designated as A, and the tangent of angle A is the ratio of Y-direction distance 33a-37 to X-direction distance 33-37. The tangent of A decreases as tracer T moves toward point 34 along line 32, thus decreasing the Y-direction distance between tracer T and scribe S, while the X-direction distance remains constant at the value 33-37. Finally, if angle A becomes zero by locating both tracer T and scribe S on the X-axis, the Y-direction distance between tracer T and scribe S is reduced to zero.

In actual practice, the tracer T is not moved to the X-axis.

The reduction in width exceeds the reduction in length in this example.

Thus, if tracer T is moved around a circle while a scribe S is in each other socket 22, said scribes S will mark a series of ellipses, each of which will have a Y-direction major axis which is shorter than the diameter of said circle, and an X-direction minor axis.

The scribe S which is in the position shown in Fig. 1 will mark the ellipse which has the shortest Y-direction major axis and the shortest X-direction minor axis.

The parts may be proportioned so that the scribes S will mark a series of scribed patterns which are of respective succeeding sizes which are smaller than the size of master pattern P.

By locating tracer T in the rear socket 22 and locating scribes S in the other sockets, the scribed patterns are larger than the master pattern.

As one example, it is assumed that the master figure is a circle, and that it is desired to mark an ellipse, the length of whose major axis is 80% of the diameter of the master circle and whose minor axis has a length which is 66 2/3% of the diameter of said master circle.

In such case, the ratio

$$\frac{26-S}{26-T}$$

must be 66 2/3%, and the ratio

$$\frac{4-S}{4-T}$$

must be 80%, in which 4-T is the distance along said common diagonal line between the axes of pivot 4 and tracer T, and 4-S is the corresponding distance between the axes of pivot 4 and scribe S. This is approximately the relation shown in Fig. 1, in which the length of each marked Y-dimension line of pattern Pa is approximately 80% of the length of the corresponding master Y-direction dimension line and the length of each marked X-direction dimension is 66 2/3% of the corresponding X-direction dimension.

As another example, it is assumed that it is

desired to mark an ellipse whose major axis is 90% of the diameter of the master circle and whose X-direction minor axis is 66 2/3% of the diameter of said master circle.

In such case, it is necessary to move scribe S closer to tracer T, so that the distance 4-S is now 90% of the distance 4-T, along said common diagonal line. This ratio remains constant in all positions of the arm.

This adjustment increases the 66 2/3% ratio of the distance 26-S to the distance 26-T along said common diagonal line. This ratio is decreased to the desired value of 66 2/3%, by shifting the pivot 26 further away from the pivot 4 along said common diagonal line, thus diminishing said width-controlling ratio to 66 2/3%.

By making the parallelogram arm elements of large size, a wide range of adjustment between relative length and width can be secured between the master figure and the marked pattern.

Fig. 3 shows that bars B have holes Ha, in order to facilitate the adjustment of their pivotal connections to the arm-elements, in order to adjust the position of pivot 26.

Fig. 4 shows a modified front arm-element E₂, in which each socket 20 is at the connecting pivot-point of a pair of bars 40 which are pivoted to the respective edge-bars by pivots 41. Fig. 4 also shows a modified construction on the inner bars of the respective arm-elements, and that holes H₁ are provided in the bars of the lazy-tongs arm, in order to facilitate the connection of bars B.

The frames 22 and 24 illustrate one convenient means for keeping the axis of pivot 26 along a single respective Y-direction line. Such means do not obstruct the pattern P, thus facilitating the accurate production of the scribed pattern Pa.

If desired, the pivot-stud 4 can be located at the pivot 15 or the corresponding central pivot point of any other arm-element, so that part of the arm may extend rearwardly of the rail 2, during the operation of the device. In such case, the pedestal 33 is sufficiently rearwardly spaced from rail 2, so that the rearwardly extending portion of the arm can move freely.

Fig. 4A shows a modification of Fig. 4, which is highly desirable to permit convenient inspection of the tracer and scribe during the operation of the machine.

Fig. 4A has the bars 50 and 51 of Fig. 4. In Fig. 4A, I provide only one bar 40 for each marking tool. The bars 40 of Fig. 4A are pivotally connected to each other by intermediate bars and pivots 52. This construction makes it unnecessary for the operator to bend down, because the tracer and scribes are clearly visible at one side, without bending down.

Instead of having only one guide-roll 3, I can use a plurality of guide-rolls 3 which are turnably connected to a bar which slides easily in the channel rail 2.

As one example, the master pattern P may be a pattern for a size 13 woman's coat. In such case, the instrument can be designed and dimensioned so that the five scribes will respectively draw patterns for sizes 16, 14, 12, 10 and 8, which is a popular range in certain classes of garment manufacture. Ordinarily the designer makes an original design pattern in size 10 or size 12. In such case, the tracer T can be located to follow the original design pattern, and the scribe S can be located to draw the corresponding patterns for the larger and smaller sizes. Optionally, any selected points of arm may be provided

with vertical rods which have anti-frictional balls or the like which are glidingly supported on the table, in order to prevent the arm from bending. The tracer T may have a small wheel at its tip. Said wheel rolls in a vertical plane along the lines of the master pattern. Said wheel is guided by turning the vertical rod of the tracer around its vertical axis, so that the plane of the wheel is always parallel to the straight line which is followed, or said plane is maintained tangent to a curved line which is followed.

I have described preferred embodiments of my invention, but numerous changes and omissions and additions and substitutions can be made without departure from the scope of my invention.

I claim:

1. In combination with a horizontal table, a horizontal and straight guide-rail on said table, a guide member movable in said guide-rail, said 20 guide member having a vertical pivot member, a lazy-tongs arm which comprises a number of arm-elements which have respective vertices which are disposed from front to rear along a straight axial line, the rear vertex being pivotally mounted on said vertical pivot member, a vertical pivot connected to said arm on said axial line between the front and rear vertices and rearwardly of the front arm-element, horizontal bearings connected to said vertical pivot, said horizontal bearings being parallel to said guide-rail, a front frame which has a front lower end and a rear upper end, said front lower end of said front frame being turnably connected to said bearings, a rear frame which has a front upper end and a rear lower end, said front upper end of said rear frame being connected to said rear upper end of said front frame by a horizontal shaft which is parallel to said guide-rail, a pedestal fixed to said table rearwardly of said guide-rail, a horizontal shaft which is parallel to said guide-rail and which connects the lower rear end of said rear frame to said pedestal, the front arm-element having a series of holders and supports for said holders which are pivotally connected to 40 said front arm-element, said holders being located on said straight axial line and being adapted to hold at least one tracer and one scribe, said lazy-tongs arm being constructed to be uniformly elongated and shortened rearwardly of said pivot and forwardly of said pivot, said pivot being always located on a line which is perpendicular to said guide-rail.

2. A marking instrument which comprises a variable-length arm which has an axis, said arm being associated with a support and overlying a supporting face of said support, said arm having a selected guide-point, guide-means adapted and operative to guide said selected guide-point in a selected straight-line guided path relative to said support, said arm also having a pivot-point and scribe-holding means for holding a scribe and tracer-holding means for holding a tracer, said pivot-point being axially intermediate said tracer-holding means and said guide-point and also axially intermediate said scribe-holding means and said guide-point, and additional guide-means for guiding said pivot-point in a pivot-point-path which is perpendicular to said guided path, said additional guide-means comprising a front frame which has a front lower end, a universal joint connecting said front lower end to said arm at said pivot-point, said front frame also having a rear upper end, a rear frame which has a front upper end, pivot-means connecting 70 said front upper end to said rear upper end of

said front frame, said pivot-means being parallel to said first-mentioned guide-means, a pedestal fixed to said table rearwardly of said frames and of said guide-means, said rear frame also having a rear lower end and additional pivot-means connecting said rear lower end to said pedestal, said additional pivot-means being also parallel to said first-mentioned guide-means.

3. A marking instrument which comprises a variable-length arm which has an axis, said arm being associated with a support and overlying a supporting face of said support, said arm having a selected guide-point, a horizontal and straight guide-rail mounted on said supporting face of said support, a guide-member movable in said guide-rail, said guide member having a vertical pivot member which is pivotally connected to said arm at said guide-point, said arm also having a pivot-point and scribe-holding means for holding a scribe and tracer-holding means for holding a tracer, said pivot-point being axially intermediate said tracer-holding means and said guide-point and being also axially intermediate said scribe-holding means and said guide-point, and additional guide-means for guiding said pivot-point in a pivot-point-path which is perpendicular to said guide-rail, said additional

guide-means comprising a front frame which has a front lower end, a universal joint connecting said front lower end to said arm at said pivot-point, said front frame also having a rear upper end, a rear frame which has a front upper end, pivot-means connecting said front upper end to said rear upper end of said front frame, said pivot-means being parallel to said first-mentioned guide-means, a pedestal fixed to said table rearwardly of said frames and of said guide-rail, said rear frame also having a rear lower end and additional pivot-means connecting said rear lower end to said pedestal, said additional pivot-means being also parallel to said first-mentioned guide-means.

WILLIAM KAUFMAN.
